Application February 9, 1942, Serial No. 429,994

12 Claims. (Cl. 24—17)

This invention relates to an article of paper or the like designed to surround or envelop, partly or wholly, some object such as an article of merchandise. Exemplary embodiments of the invention hereinafter described are stationery envelopes and tie bands such as are used in laundries to hold laundered and ironed shirts properly folded, but it will be apparent that the invention can readily be embodied in other kinds of enveloping articles wherein the article is to be secured by cementing one portion thereof to another.

Articles of this kind have previously been secured by the application thereto of an adhesive (such as paste or glue) from an external source at the time of use. Also, suitable areas of inactive adhesive (e. g., dried glue) have been supplied on such articles to be activated by a suitable solvent (water) when wanted for use.

According to the present invention, a surrounding or enveloping article (such as an envelope, wrapper, tie band or the like) is provided which is self-contained, i. e., needs no extra material to be applied at the time of use, is quickly and easily secured, and is economical to manufacture. To this end, the article is made with at least one portion folded over so as to be in face to face engagement with another portion thereof, the mutually engaging faces having thereon respectively an area of permanently sticky or tacky coating material and an area of insulating material, such as wax, which will make a weak bond with the sticky material so that the mutually engaged faces of the article can be readily pulled apart when the article is to be put to use.

For a more complete understanding of the invention, reference may be had to the following description of illustrative embodiments thereof, and to the drawings of which

Figure 1 is a rear elevational view of an envelope embodying the invention.

Figure 2 is a section on the line 2—2 of Figure 1.

Figure 3 is a partial rear elevational view of an envelope ready for packaging.

Figure 4 is a section on the line 4—4 of Figure 3.

Figure 5 is a partial elevational view of an envelope in its sealed condition.

Figure 6 is a partial elevational view of a modified form of the invention.

Figure 7 is a section on the line 7—7 of Figure 6.

Figure 8 is a sectional view of the envelope shown in Figures 6 and 7 in sealed condition.

Figure 9 is a plan view of a tie band embodying the invention.

Figure 10 is a side edge view of the same.

Figure 11 is a similar view of the band ready for packaging.

Figure 12 is a side edge view of the band applied to an object.

5 Figure 13 is a plan view of a modified form of the band.

Figure 14 is a side edge view of the same ready for packaging.

Figure 15 is a side edge view of the same when applied to an article.

Figures 16 and 17 are fragmentary plan views of other modified forms of the invention.

Figure 18 is a plan view of another form of tie band.

15 Figure 19 is a side elevation of a package of tie bands such as that shown in Figure 18.

Figure 1 shows a surrounding or enveloping article in the form of a stationery envelope 10 having the usual side flaps 12, a lower flap 14 extending up from the lower edge of the envelope, and an upper flap 16 which is foldable down to overlap the upper portion of the lower flap 14 to seal the envelope. The upper end portion or tab 20 of the lower flap 14, according to the invention,

20 is folded down against the adjacent portion 22. The upper flap 16 is of sufficient length to overlie the folded tab 20 as indicated in Figures 3 and 4.

25 When the flap is thus folded down, the tab 20 lies between a portion of the flap 16 and the adjacent portion 22 of the lower flap 14, these three parts of the envelope being thus in face to face engagement.

30 One or both of the faces of the tab 20 are coated with suitable insulating material which is characterized by being substantially non-adher-

35 ent, or only weakly adherent to permanently sticky coating material which is applied to other surfaces of the envelope as hereinafter described.

The term "insulation" as hereinafter used in the specification and claims is intended to refer to

40 such material as does not appreciably adhere to sticky adhesive material. For this purpose, I may employ materials which are of waxy, greasy or oily character—paraffin wax being desirable by reason of its availability and low cost.

45 The face or faces of the flap 16 and portion 22 of the flap 14 which are engaged by the waxed face or faces of the tab 20 are provided with one or more areas of permanently sticky adhesive material from which the waxed surface can readily be separated but which will make a firm bond

50 with any portion of the envelope not protected by such insulating coating. For example, as

55 shown in Figures 3 and 4, the inner face of the folded tab 20 is coated with waxy insulating material as at 24. The face of the adjacent portion

22 of the flap 14 which is engaged by the waxed face of the tab 20 is provided with a coating 26 of permanently sticky adhesive material. The tab 20 thus serves to cover the sticky area and to protect it from accidental contact with some other part of the envelope. When it is desired to seal the envelope, the tab 20 is swung back into the plane of the flap 14, as illustrated in Figures 1 and 2, with the aid of the extreme end portion of the tab which extends beyond the sticky area 26 and is thus free and is easily grasped. Then the flap 16 is folded down so that its end portion engages the gummed area 30 and permanently adheres thereto.

In some cases it may be desired to provide a firmer bond by constructing the envelope so that, when it is sealed, two pre-coated areas are brought into face to face engagement with each other to make the sealing bond, these areas being coated with suitable, permanently sticky, adhesive material. Such an envelope is illustrated in Figures 6, 7 and 8 wherein a coating of permanently sticky gum 30 is applied to the portion of the flap 16 which engages the folded tab 20. In this case, both surfaces of the fold of the tab 20 are coated with insulating material 24 and 31 such as wax so that the gummed surface 30 normally engages the insulated outer face of the folded tab 20. When the tab 20 is swung up to its position in the plane of the flap 14, the gummed coating 26 on the portion 22 is thereupon exposed for engagement by the coated area 30 when the flap 16 is folded down. This brings two gummed areas into mutual engagement to form a firm sealing bond as indicated in Figure 8.

If desired, when the flap 16 is provided with a gummed coating 30 and the outer face of the folded tab 20 is coated with wax or other insulating material 31, the wax coating on the inner face of the tab and the gum coating on the portion 22 of the flap 14 may be omitted. In such case, the gummed area 30 will normally engage the waxed outer face of the tab 20, but when the envelope is to be sealed the tab 20 is swung up to expose an uncoated area of the flap 14 for engagement by the gummed area 30.

Instead of waxy or greasy preparations for insulating areas of the flap 20, I may use any other equivalent surface such as will make only a weak bond with the sticky material used on engaged faces. For example, the smooth side of holland cloth or a suitably glazed paper surface may be sufficiently non-adherent to the sticky material to serve as an insulated surface.

Any suitable, permanently sticky, adhesive gum may be employed in the manner hereinbefore described. Several such adhesives are well known in the art and may include glues of various kinds, resins or resin derivatives, or any other suitable substances which may be mixed with other substances to provide a permanently sticky adhesive suitable for coating. For example, I may prepare a gum of this description by soaking 15 pounds of glue in 20 pounds of water, sufficient heat being applied to form a solution. To this solution is added 21 pounds of yellow glycerine. After the glycerine has been thoroughly mixed in, 5 pounds of water are added. This produces a permanently sticky adhesive which may have to be thinned by the addition of more water for application to certain types of paper surfaces.

Figures 9 to 12 inclusive illustrate another embodiment of the invention consisting of a tie band such as is used in merchandising certain articles such as gloves, neckties, socks and the

like, or by laundries in holding laundered or ironed shirts in folded position. Bands of this kind are preferably provided with one or more adhesive areas by which the ends of the bands can be attached when the band is applied to merchandise which it surrounds. According to the present invention, a permanently sticky adhesive area is supplied on one face of one extremity or end portion of the band, this end portion being folded over against a closely adjacent portion of the band so as to be in face to face engagement therewith. The engaged face of such adjacent portion is previously coated with suitable insulation such as wax or an equivalent so that whatever bond is created by the adhesive between the folded tab and the body of the strip is very weak. The separation of the sticky surface from the insulation is easily accomplished by grasping with the finger and thumb a free ungummed tab at the extremity of the gummed end portion and drawing it in the direction of the other end of the band when it is stretched around the article. The slight tension overcomes the weak bond between the gummed portion and the insulated surface. This obviates the necessity of first folding the end section back. Thus as shown in Figures 9 and 10, a band 40 is provided having an end portion 42 with an area 44 of permanently adhesive gum. Adjacent to the end portion 42 is another portion 46 having an insulation coating 48 of wax or an equivalent. When the band is prepared for packing with other similar bands, the end portion 42 is folded over against adjacent portion 46 as indicated in Figure 11, the entire sticky area 44 being against the waxed area 48. The sticky area 44 is preferably spaced from the adjacent side and end edges of the strip, as shown in Figure 9, leaving an ungummed end area 50 and ungummed marginal areas 51. The end area 50 provides a free tab which can readily be grasped by the operator when it is desired to pull the tab 42 free from the portion 46. This is done as the band is being applied to the object 52 which is to be embraced thereby as illustrated in Figure 12. The gummed area 42 is thus readily exposed for application to the opposite end portion of the band. As this end portion is not insulated, a good bond is produced.

The uncoated margins 51 obviate the necessity for accurate registration of the end portions which are brought together. Accurate registration would be necessary if the sticky coating extended to the edges as otherwise some of the coated area would come into contact with the merchandise. Such gum-free margins are also advantageous in the manufacture of the bands if they are cut from sheets after the gum has been applied. The knife would then cut through gum-free areas.

If it is desired to make the bond by applying two gummed areas to each other, both ends of the band may be treated as hereinbefore described, the end portions being folded against the opposite faces of the body of the band. Thus, as illustrated in Figures 13 and 14, a gummed area 44 is folded over against an insulated area 48. At the other end of the band 40 a gummed area 54 on the under face of the strip is folded under so as to engage an insulated area 56 which is also on the under face of the band. The extremities of both folded portions are preferably left uncoated so as to provide finger tabs 50 to facilitate grasping the folded portions. When the band is applied to

an article of merchandise, the folded end portions are pulled back to expose their sticky areas. These areas are then brought into face to face contact after the band has been passed around the article of merchandise as illustrated in Figure 15.

Instead of the single area 44 or 54 of sticky coating, a plurality of smaller areas may be provided, two such areas 60 being shown in Figure 16 by way of example.

For some purposes it may be desirable to extend the sticky coating to the edges of the band as illustrated at 62 in Figure 17.

Figure 18 illustrates a tie band characterized by an area 44 of material which is not generally tacky or adhesive but which is cohesive in the sense that it holds strongly to a similarly coated area when pressed thereagainst, the coating on one area thus cohering with the coating on the other area. For this purpose I use a rubber-free coating material which is generally non-adherent, but which sticks to another similar coating when brought into contact therewith. Neoprene latex, a so called synthetic rubber put out by the Du Pont Company, is such a material and is one which I have found eminently satisfactory. End areas 58 and marginal areas 42 may be left uncoated as hereinbefore described. Since in this embodiment of the invention the coated areas are not adhesive, no insulated areas are ordinarily required, provided that the bands are packed in such a way that the coated areas do not touch any other coated areas. In some cases, however, it may be preferred to provide insulated areas 66 in registry with the coated areas at opposite sides of the strip from the respective coated areas to be engaged by the coated areas 44 of adjacent strips in the package. As indicated in Figure 19, bands having a coating of cohesive (as distinguished from adhesive) material may be packaged flat, that is, without preliminary folding; and this may be done whether or not the bands are provided with the insulation 66 shown in that figure.

It is evident that various modifications and changes may be made in the embodiments of the invention herein shown and described without departing from the spirit or scope thereof as defined in the following claims.

I claim:

1. An envelope including a lower flap having its upper end portion folded back so as to be in face to face engagement with an adjacent portion thereof, and an upper flap extending down to engage upon said folded portion of the lower flap, one of the faces of said folded portion of the lower flap having a coating of waxy insulating material thereon, the surface engaged by said coated face being coated with a permanently sticky adhesive material.

2. An envelope including a lower flap having its upper end portion folded back so as to be in face to face engagement with an adjacent portion thereof, and an upper flap extending down to engage upon said folded portion of the lower flap, both faces of said folded portion of the lower flap being coated with waxy insulating material, the surfaces engaged by said coated faces having areas of permanently sticky adhesive coating thereon.

3. An envelope including a lower flap having its upper end portion folded back so as to be in face to face engagement with an adjacent portion thereof, and an upper flap extending down

5 to engage upon said folded portion of the lower flap, said adjacent portion of the lower flap having an area of permanently sticky coating material thereon, the opposed face of said folded portion of the lower flap having a wax coating thereon to facilitate separation of the mutually engaged faces.

4. A tie band comprising a strip of flexible material having one extremity folded over 10 against a closely adjacent portion of the body, which is remote from the opposite extremity and in face to face engagement therewith, the engaged face of said extremity having an area coated with permanently sticky adhesive, the engaged face of said adjacent portion having a coating of insulating material which is substantially non-adherent to said adhesive.

5. A tie band comprising a strip of flexible material having one extremity folded over 15 against a closely adjacent portion of the body, which is remote from the opposite extremity and in face to face engagement therewith, the engaged face of said extremity having an area coated with permanently sticky adhesive, the engaged face of said adjacent portion having a coating of wax thereon.

6. A tie band comprising a strip of flexible material having one end portion folded over 20 against the obverse face of the adjacent body portion and in face to face engagement therewith, the other end portion of the strip being folded under against the reverse face of the body portion adjacent thereto and in face to face engagement therewith, the engaged face of each 25 said end portion having an area coated with a permanently sticky adhesive material, the engaged face of each said adjacent portion having a coating of material which is substantially non-adherent to said adhesive material.

7. A tie band comprising a strip of flexible material having its opposite extremities bent back in respectively opposite directions upon the 30 respectively adjacent portions of the strip and in face to face engagement therewith, the engaged face of each said extremity having an area of permanently sticky coating thereon spaced from the adjacent edge of the strip to provide an uncoated end tab to be gripped by the fingers of an operator, the engaged faces of

35 50 said adjacent portions of the strip having a coating of waxy material which is substantially non-adherent to said sticky coating.

8. A tie band comprising a strip of flexible material having an end portion folded over 55 against a closely adjacent area of the strip and in face to face engagement therewith, the engaged face of said end portion having thereon a plurality of permanently sticky areas thereon 60 spaced from each other and from the adjacent end and side edges of the strip, the engaged area of said adjacent portion having thereon a coating of material which is substantially non-adherent to said sticky areas.

9. A tie band having adjacent to each end an area having a rubber-free coating which is substantially non-adherent but which will cohere with a similar coating when brought into contact therewith.

70 10. A tie band having on opposite faces and adjacent respectively to opposite ends a rubber-free coating consisting essentially of an intimate mixture of glue and glycerine.

11. An article of paper or other thin flexible material adapted to be put in surrounding rela-

tion with other things with opposite extremities of said article overlapping and bonded together, one of the end portions of said article having on contiguous areas of one surface thereof a coating of permanently adhesive material and a coating of material which is substantially non-adherent to said adhesive respectively, said extremity, when the article is not in use, being folded between the said contiguous areas so that the areas are in face to face contact and the adhesive coating is protected from contact with other surfaces.

12. An article of paper or other thin flexible material adapted to be put in surrounding relation with other things with opposite extremities of said article overlapping and bonded together, one of the end portions of said article having on contiguous areas of one surface thereof a coating of permanently adhesive material and a coating of wax, and being folded on a line between said areas so that the adhesive and wax coatings are in face to face engagement.

RALPH H. WILBUR.
